US0D1014095S

(12) **United States Design Patent** (10) **Patent No.:** **US D1,014,095 S**
(45) **Date of Patent:** **** Feb. 13, 2024**

(54) **TOOTHBRUSH**

(71) Applicant: **The Gillette Company LLC**, Boston, MA (US)

(72) Inventors: **Uwe Jungnickel**, Königstein (DE); **Dominik Langhammer**, Frankfurt (DE); **Christine Hallein**, Frankfurt (DE); **Jens Störkel**, Frankfurt (DE)

(73) Assignee: **The Gillette Company LLC**, Boston, MA (US)

(**) Term: **15 Years**

(21) Appl. No.: **29/762,790**

(22) Filed: **Dec. 18, 2020**

(30) **Foreign Application Priority Data**

Jul. 2, 2020 (WO) WIPO96062

(51) **LOC (14) Cl.** **04-02**

(52) **U.S. Cl.**
USPC **D4/110**

(57) **CLAIM**

The ornamental design for a toothbrush, as shown and described.

DESCRIPTION

FIG. 1 is a perspective view of a first embodiment of a toothbrush;

FIG. 2 is a front view thereof;

FIG. 3 is a left-side view thereof;

FIG. 4 is a rear view thereof;

FIG. 5 is a right-side view thereof;

FIG. 6 is a top view thereof;

FIG. 7 is a bottom view thereof;

FIG. 8 is a perspective view of a second embodiment of a toothbrush;

FIG. 9 is a front view thereof;

FIG. 10 is a left-side view thereof;

FIG. 11 is a rear view thereof;

FIG. 12 is a right-side view thereof;

FIG. 13 is a top view thereof; and,

FIG. 14 is a bottom view thereof.

The broken lines in the drawings depict portions of the toothbrush that form no part of the claimed design.

1 Claim, 4 Drawing Sheets
